UNITED STATES PATENT OFFICE

WALTER J. STUBER, OF PHILADELPHIA, PENNSYLVANIA, ASSIGNOR TO CAREY-MCFALL CO., OF PHILADELPHIA, PENNSYLVANIA, A CORPORATION OF PENNSYLVANIA

CURTAIN PULL

Application filed August 16, 1930. Serial No. 475,706.

This invention relates to a curtain pull for use with window shades, and particularly those employed in automobile bodies of the closed type. In the more expensive automobiles the curtain pulls are in the form of silk cords and tassels, while in the less expensive cars the curtain pulls usually comprise merely a folded piece of shade material stitched to the hem of the curtain, which, unless extreme care is exercised when assembling the curtain elements, produces a very displeasing effect.

The object of my invention is to provide an inexpensive curtain pull of a relatively rigid nature, which may be readily applied to the curtain without sewing, and which presents an appearance in keeping with all classes of automobiles regardless of their price.

Fig. 1 illustrates a curtain pull made in accordance with the principles of my invention, and applied to a window shade such as used in closed automobiles;

Fig. 2 is an enlarged front view of a portion of the curtain with the curtain pull applied thereto;

Fig. 3 is a sectional elevational taken on the line 3—3, Fig. 2; and

Fig. 4 is a development of the blank from which the curtain pull is made.

The blank shown in Fig. 4 is adapted to be punched or cut from a sheet of suitable material, and for the purpose of economy I propose to use sheet metal of a kind adaptable for the purpose.

The blank illustrated in Fig. 4 comprises a center bottom portion 1, flanked on its opposite sides by finger-grip portions 2, 2^a respectively. At the outer ends of the finger-grip portions 2, 2^a are head or clamp portions 3, 3^a, respectively. Extending laterally from the oppositely disposed side edges of the finger-grip portions 2, 2^a are flange portions 4, 4^a and 4^b, 4^a respectively. In the finger-grip portions 2, 2^a are apertures 5, 5^a respectively.

The head or clamp portions 3, 3^a are adapted to be bent into a substantially semi-circular form between the lines a , a' and the ends 6, 6^a of the blank respectively. The finger-grip portions 2, 2^a are adapted to be bent on the lines b , b' substantially at right

angles to the plane of the bottom portion 1 and in directions toward each other until the said finger-grip portions 2, 2^a engage each other at points adjacent the lines a , a' , as clearly shown in Fig. 3, the bottom portion 1 of the blank maintaining the opposite ends of the finger-grip portions 2, 2^a in spaced relation to each other as clearly shown in Fig. 3.

In order to close the space between the said finger-grip portions the flanges 4, 4 and 4^a, 4^b are bent inwardly along the lines c , c and c' , c' into a plane substantially at right angles to the plane of the finger-grip portions 2, 2^a.

In the present instance I have shown the usual form of shade, indicated at 10, which is wound on a suitable roller rotatably supported in brackets 11, 11, the shade 10 being provided with a suitable hem 12 in which is mounted a pull rod 13, eyelets 14, 14 being provided at the ends of the draw rod adjacent the oppositely disposed side edges of the curtain 10, for the reception of the usual guide cords 15, 15 which prevent flapping of the curtain when the automobile is in motion.

The curtain pull 20 which has been finally shaped in the manner above noted, is adapted to be applied to the window shade by placing the split head or clamp portions 3, 3^a in contact with the front and back sides respectively of the hem 12 of the curtain and passing a rivet or other suitable fastening device 16 through the openings 5, 5^a in the finger-grip portions 2, 2^a respectively, whereby the edges 7, 7 of the flanges 4, 4 of the finger-grip portion 2, are brought into abutting relation to the edges 7^a, 7^a of the flanges 4^a, 4^b of the finger-grip portion 2^a, and the split head clamp portions 3 and 3^a are forced into gripping contact with the hem 12 of the curtain around the pull rod 13 therein, thus the curtain pull is rigidly secured to the curtain with the minimum amount of labor and in a manner presenting a very pleasing appearance.

In order to facilitate the operation of the curtain by means of the curtain pull 20, I have formed the abutting edges 7 and 7^a of the flanges 4 and 4^a as curves which, when brought into abutting relation to each other, cause the curtain pull to assume an arcuate form curving outwardly from the general

plane of the curtain to which the pull is applied, whereby the finger plates 2 and 2^a may be more readily gripped between the thumb and first finger for more conveniently raising or lowering the curtain.

If the curtain pull is formed of metal, such as sheet iron, steel, or brass, it may be plated with nickel or chromium to produce a bright finish, or it may be painted any desired color 10 to correspond to the color of the curtain or other trimmings within the automobile.

While I have described the curtain pull as being made of sheet metal bent into form, obviously the curtain pull could be molded in 15 hard rubber, bakelite or similar material having a sufficient amount of resiliency to permit the split head clamp portions 3, 3^a to be sprung over the curtain rod and thus eliminate the fastening 16, or the clamp portion 20 3, 3^a may be formed as a solid head having an opening passing axially therethrough for the reception of the draw rod 12 without departing from the essential features of the invention.

25 I claim:

1. A curtain pull composed of sheet material and formed from a blank comprising a central portion forming the bottom of the pull, a finger-grip portion on each side of the 30 central portion, a head portion forming a continuation of each finger-grip portion, and a flange portion along each of the opposite side edges of each of the finger-grip portions.

2. A curtain pull composed of sheet material and formed from a blank comprising a central portion forming the bottom of the pull, a finger-grip portion on each side of the central portion, a head portion forming a continuation of each finger-grip portion, and a 40 flange portion along each of the opposite side edges of each of the finger-grip portions, the edges of flanges of each finger-grip portion flaring outwardly relative to the longitudinal center line of the blank from the lines of junction of the head portions and the finger-grip portions to the lines of juncture of the finger-grip portions and the central bottom portion, whereby when the blank is bent into final 50 shape the said finger-grip portion will be wedge shaped in cross section with the narrow portion of the wedge adjoining the head portion of the pull.

3. A curtain pull composed of sheet material and formed from a blank comprising 55 a central portion forming the bottom of the pull, a finger-grip portion on each side of the central portion, a head portion forming a continuation of each finger-grip portion, and a flange portion along each of the opposite 60 side edges of each of the finger-grip portions, the edges of flanges of each finger-grip portion flaring outwardly relative to the longitudinal center line of the blank and formed as curves extending from the lines of juncture 65 of the head portions and the finger-grip por-

tions to the lines of juncture of the finger-grip portions and the central bottom portion, whereby when the blank is bent into final shape the said finger-grip portion will be wedge shaped in cross section with the narrow portion of the wedge adjoining the head portion of the pull with the curtain pull split along its said longitudinal center line which will be disposed on an arc bisecting the curtain pull throughout its length.
